VACUUM CLEANER

Hilland G. Hunt, Natick, Mass.

Application October 15, 1940, Serial No. 361,247

6 Claims. (Cl. 15—8)

This invention relates to a vacuum cleaner.

In general, one object of the invention is to provide a novel and improved vacuum cleaner of the type having agitating means mounted in the cleaning nozzle wherein provision is made for operating the agitating means in a novel economical and practical manner.

The invention has for a further object to provide a novel and improved vacuum cleaner having a rotary brush or agitator in the cleaning nozzle and in which provision is made for pneumatically driving the rotary brush or agitator in a novel practical and economical manner.

With these general objects in view and such others as may hereinafter appear, the invention consists in the vacuum cleaner and in the various structures, arrangements and combinations of parts hereinafter described and particularly defined in the claims at the end of this specification.

In the drawing illustrating the preferred embodiment of the invention, Fig. 1 is a cross-sectional view of a vacuum cleaner of the tank or cylinder type embodying the present invention; Fig. 2 is an enlarged view in cross-section of a modified form of the cleaning nozzle shown in Fig. 1; and Fig. 3 is a side elevation, partly in cross section of the cleaning nozzle.

In general, the present invention contemplates a novel and improved electric vacuum cleaner of the type with agitating means mounted in the cleaning nozzle in which provision is made for actuating the agitator from a source of power remote from the nozzle. Heretofore, prior electric vacuum cleaners employing a rotary agitating element in the suction nozzle have been motor driven, some directly from the suction creating motor by means of a belt or other connection. This method of driving the rotary agitator has required a motor in proximity to the agitator and has precluded the utilization of such agitators in vacuum cleaners of the so-called tank type.

In accordance with the present invention, the nozzle mounted agitator may be driven from the suction creating or other motor disposed remotely from the cleaning nozzle and in the illustrated embodiment of the invention, such connections include a pneumatically driven impeller element mounted in the nozzle and a conduit connected to the exhaust end of the vacuum cleaner to operate the air driven element by the air being exhausted from the cleaner during the cleaning operation.

Referring now to the drawing which illustrates the preferred embodiment of the invention, 10 represents a vacuum cleaner of the so-called tank or cylinder type having an inlet 12 at one end and an exhaust outlet 14 at the other end. The illustrated vacuum cleaner is provided with the usual suction creating unit including an electric motor 16 and fan 18 at one end of the tank, and

5 a dust receiving bag 20 is secured to the inlet end. Suitable filtering elements indicated generally at 22 may also be provided between the bag and the fan.

10 The inlet end of the tank 10 is connected by a hose 24 and extension tubes 26 to a nozzle unit indicated generally at 28. The nozzle unit 28 is provided with a rotary brush or agitator 30 rotatably mounted in ball bearings 32 carried in the nozzle casing 34. As herein shown, at least one and preferably both ends of the brush shaft 36 may be provided with an impeller wheel or rotary motor 38 fast thereon and adapted to be actuated by air pressure. The impellers 38 are fitted in bores 40 provided in the ends of the nozzle casing, and cover plates 42 are fitted over the bores to enclose the impellers in chambers 44. Each chamber 44 is provided with an air inlet 46 arranged to direct a stream of air onto the blades 48 of the impeller to effect rotation thereof, the exhaust air being permitted to escape through an outlet 50 disposed in the lower portion of the chamber.

20 As herein illustrated, the air for actuating the rotary motor 38 may and preferably will comprise the exhaust air from the vacuum cleaner, although it is not desired to limit the invention in this respect. The exhaust end 14 of the tank 10 is provided with a curved fitting 52 arranged to direct the exhaust air through a pipe connection 54, and flexible hose 56 which leads to the air inlet 46 of each chamber 44. The hose 56 may be provided with an attachment fitting 58 to permit the hose to be conveniently disconnected from the tank unit 10 when desired. The curved fitting 52 is provided with a removable cap member 60 which may be removed to permit the exhaust air to escape in the usual manner when it is desired to discontinue rotation of the rotary brushes or agitators 30. As herein shown, the hose 56 is preferably progressively decreased in size in order to impart increased velocity to the air stream and consequently to effect a relatively rapid rotation of the rotary motor 38. The rotary cleaning element, herein illustrated as a brush 30 may be made in any usual or preferred form such as a brush having bristles in straight lines or staggered rows, indicated in Fig. 2, or the bristles may be spirally arranged as shown in Fig. 1.

30 Referring now to the nozzle unit 28, the nozzle casing 34 is preferably mounted on wheels 62 in order to dispose the nozzle inlet 64 a slight distance above the surface to be cleaned so that 35 in operation over a carpet or rug, the suction operates to draw the carpet or rug up into the nozzle inlet into a position to be brushed or agitated by the brush or agitator 30 so that the combined agitating and pneumatic action serves 40 to perform an efficient cleaning operation. The

extension tube 28 which serves as a handle for the nozzle unit may be connected to the latter by a universal connection of any usual or preferred form, generally indicated at 65.

From the description thus far, it will be observed that the present invention avoids the disadvantages inherent in the direct connected methods heretofore employed in driving the rotary agitators of prior vacuum cleaners, and permits the agitator in the nozzle to be driven from a source remote from the nozzle, thus enabling vacuum cleaners of the tank type to successfully utilize an agitator in the nozzle thereof.

In addition to its utility when embodied in a vacuum cleaner as herein illustrated, the pneumatic driving mechanism may be used with advantage in other comparable machines when it is desired to rotate a rotary element from a motor disposed remote from the rotary element, such for example, as in waxing, or polishing machines.

While the preferred embodiment of the invention has been herein illustrated and described, it will be understood that the invention may be embodied in other forms within the scope of the following claims.

Having thus described the invention, what is claimed is:

1. A vacuum cleaner having, in combination, a chamber having an inlet and an outlet, a motor driven fan in said chamber arranged to create a suction in said inlet and to discharge exhaust air from said outlet, a cleaning nozzle connected to said suction inlet, a rotary agitating member carried by said nozzle, and connections between said exhaust outlet and said rotary member constructed and arranged to pneumatically drive said rotary member with the exhaust air stream, said exhaust outlet being provided with a removable cap member, upon removal of which the pneumatic drive to said rotary member may be discontinued.

2. In a vacuum cleaner, in combination, suction creating means, a cleaning nozzle operatively connected with the suction creating means and through which the air for performing the cleaning operation is drawn by the suction creating means, a rotary agitator mounted within the nozzle in position to engage the surface to be cleaned when the mouth of the nozzle is drawn across such surface, and pneumatically operated means for rotating the agitating device comprising an impeller member operatively connected to the agitating device, a chamber enclosing the impeller member, said chamber being mounted upon and in non-communicating relation to the nozzle and having an air inlet and an air outlet, the latter being arranged to discharge air outside of the nozzle, and a conduit operatively connected to said suction creating means and connected with said inlet for conducting thereto exhaust air after the latter has passed through the cleaning nozzle and has performed the cleaning operation whereby to effect the operation of the impeller member without diminishing the suction at the mouth of the nozzle.

3. In a vacuum cleaner, in combination, a portable tank provided with an inlet at one end and an outlet at the opposite end, a cleaning nozzle, a flexible conduit connecting the tank inlet with the nozzle, a suction creating device within the tank, a dust-collecting bag within the tank through which air is sucked from the clean-

ing nozzle through said flexible conduit by said suction creating device to be discharged through said tank outlet, a rotary agitator mounted within the nozzle in position to engage the surface to be cleaned when the mouth of the nozzle is drawn across the surface, pneumatically operated means for operating the agitating device comprising an impeller member connected with the agitating device, a chamber enclosing the impeller member and having an inlet and an outlet, said chamber being mounted upon and separated from the nozzle, and the outlet being disposed to discharge air outside of the nozzle, and a flexible conduit connecting the tank outlet with said impeller chamber inlet, whereby to effect the operation of the impeller member by the exhaust air after the air has performed the cleaning operation without diminishing the suction at the mouth of the nozzle.

4. In a vacuum cleaner, in combination, suction creating means, a cleaning nozzle operatively connected with the suction creating means and through which the air for performing the cleaning operation is drawn by the suction creating means, a rotary agitator mounted within the nozzle in position to engage the surface to be cleaned when the mouth of the nozzle is drawn across such surface, a pneumatically operated device comprising two impeller members connected to opposite ends of the agitating device, separate impeller receiving chambers each having an inlet and an outlet mounted upon the nozzle housing and separated from the interior of the nozzle, and conduits operatively connected to the suction creating means and to the impeller receiving chamber inlets for conducting exhaust air to said inlets to operate said impeller members without diminishing the suction at the nozzle.

5. In a vacuum cleaner, in combination, a portable tank provided with an inlet and an outlet, suction creating means within the tank, a dust collector within the tank between the outlet and said suction creating means, a cleaning nozzle, a long flexible conduit operatively connecting the nozzle with the tank inlet and through which the air for performing the cleaning operation is drawn by the suction creating means, a rotary agitator mounted within the nozzle in position to engage the surface to be cleaned when the mouth of the nozzle is drawn across such surface, and pneumatically operated means for rotating the agitating device comprising an impeller member operatively connected to the agitating device, an impeller chamber enclosing the impeller member in non-communicating relation to the nozzle and having an air inlet and an outlet, said outlet being disposed to discharge air outside of the nozzle, and a flexible conduit connected to said impeller chamber inlet for supplying air under pressure to operate said impeller member.

6. In a vacuum cleaner, the combination comprising: a cleaning nozzle having a chamber formed therein adapted to receive agitator means, means for creating a suction in said cleaning nozzle chamber, agitator means in said cleaning nozzle chamber, means including a source of air under pressure for operating said agitator means, and means for discharging spent agitator operating air at a point outside the nozzle chamber.

HILLAND G. HUNT.
